UNITED STATES PATENT OFFICE.

ALLEN E. OSTRANDER, OF PATERSON, NEW JERSEY, ASSIGNOR TO
AMERICAN CAR & FOUNDRY COMPANY, OF ST. LOUIS, MISSOURI,
A CORPORATION OF NEW JERSEY.

CAR-SEAT.

No. 810,558.

Specification of Letters Patent.

Patented Jan. 23, 1906.

Application filed July 26, 1905. Serial No. 271,342.

To all whom it may concern:

Be it known that I, ALLEN E. OSTRANDER, a citizen of the United States, residing at Paterson, Passaic county, New Jersey, have invented a certain new and useful Improvement in Car-Seats, of which the following is a full, clear, and exact description, such as will enable others skilled in the art to which it appertains to make and use the same, reference being had to the accompanying drawings, forming part of this specification, in which—

Figure 1 is a view in elevation of a car-seat constructed in accordance with my invention. Fig. 2 is a disassociated view of the several parts of which the car-seat is constructed. Fig. 3 is an elevational view of the bracing angles. Fig. 4 is a disconnected view of the gusset - plate car side and one of the cross-bearers; and Fig. 5 is a view in elevation of the car-seat next to the car side.

This invention relates to car-seats; and one of the objects thereof is to provide a car-seat preferably formed of metal and so combined with the car-body as to increase the strength thereof and obviate the necessity of bracing, owing to the fact that part of the car-seat structure may be utilized for this purpose.

In the form illustrated in the drawings, 1 indicates one of a number of cross-bearers in the form of channels, which extend from side sill to side sill, and 2 indicates one of the side sills, each of which comprises an angle having its horizontal flange inwardly disposed and its vertical flange outwardly disposed. The verticals of the side posts 3, as well as the cripple-posts under the windows, are connected to the cross-bearers and support the plate-girder sides 4 of the car.

5 designates a gusset which is riveted along one vertical edge to one of the posts 3, which posts may consist of two angles riveted together and which has its lower edge extending below the floor and fast to the cross-bearer 1 by any suitable means, as by rivets 6, which pass through said cross-bearer, gusset, and an angle 7, the horizontal flange of said angle in combination with the top flange of the channel forming a floor-support. At the inner edge, or at the edge nearest the center of the car, the gusset is connected to the outstanding flanges 8 and 9 of the vertical standard comprising the pressed-steel seat ends 10 and 11. These flanges 8 and 9 are spaced

apart a distance equal to the thickness of the gusset, so that the gusset may be interposed between them and secured by rivets. The edges of the standard are inclined toward each other in an upward direction, or, in other words, have a tendency to converge upwardly at an angle of inclination corresponding to the angle of inclination of the backs of the seat, it being understood that the device is preferably a twin-seated construction having a double back. Riveted along the inclined edges of said standard are angles 12 and 13.

These angles extend beyond the upper extremities of the flanges on the seat-front and consist of one or more pieces, which extend across the back of the seat and down on the side next to the car-wall, and they are riveted together at the top and form the support for the seat-back cushion. A top cover-plate 15 rests upon the top flanges 14 and is bent downwardly over the side of the vertical standard to form a cover portion 16, overlapping the joint made by the connection of the parts 10 and 11, so as to provide a finish for the seat. The lower ends of the angles 12 and 13 are connected to the angles 17, which are supported by the standard and the car side, the horizontal flange of each angle 17 resting upon the horizontal rib 18 of each casting 19. The castings 19 are oppositely disposed and are connected to the respective members 10 and 11 by the arms 20 and 21, and the front portions of each seat are connected by the angles 22, which are riveted to the ribs 18 and to the sides of the car. The skeleton structure thus set up may be filled in with cross bars or sheets, so as to receive the seat-cushions 23 and the back-cushions 24, or the cushions may rest directly upon the angles 17 and 22, being kept in place by stops on the bottom of the cushion-frame. At the side of the car the gusset is provided with angles 25 and 26, having oppositely-disposed flanges 27 and 28, which support angles 29 and 30, to which the angles 22 are secured, and the angles 17 are connected to angles 12^a and 13^a, respectively, which angles 12^a and 13^a are fastened to the gusset 5 by means of channel connection-plates 31 and 32. The upper portions of said angles 12^a and 13^a are riveted together, as are the upper portions of the angles 12 and 13. The angles 29 and 30 are

also screwed to the wood furring-strips connected to the sides of the car.

It will be observed that the car-seat will be rigid, light, and durable, and the arrangement of the strengthening parts, such as the angles and the gusset, which extend below the floor-level, will materially strengthen the car-body. By utilizing a construction of car-seat with the bracing-gussets as heretofore described the ordinary center sills for the underframing may be dispensed with. However, the construction herein disclosed might also be utilized in a car having center sills.

Having thus described the invention, what is claimed as new, and desired to be secured by Letters Patent, is—

1. In a car-seat, the combination with the cross-bearers of the underframing and the sides of a car, of a gusset secured to the side of the car and extending down along side of the cross-bearer, fastening devices extending through said gusset and cross-bearer a standard fastened to one end of the gusset, a seat-cushion support connected to said standard, a back-cushion support connected to said standard and to said seat-cushion support, and a connection between said seat-cushion support and the side of the car; substantially as described.
2. The combination with the underframing of a car and the car side, of braces connected to the car side and extending below the floor, connecting devices extending through the underframing and the braces below the floor of the car, a standard connected to one of the braces distant from the side of the car, a connection between the upper portion of the standard and the car side; a seat-cushion support secured to the standard, and a connection between the seat-cushion support and the side of the car; substantially as described.
3. In a car, the combination with channel cross-bearers and plate-girder sides, of a gusset riveted to the plate-girder sides and extending down beside one of the cross-bearers, connecting devices extending through said cross-bearer and gusset below the floor of the car, a standard carried by said gusset and

distant from the side, means for supporting a seat-cushion and connected to said standard, and connections between the standard and seat-cushion support and the plate-girder side; substantially as described.

4. In a railway-car, the combination with channel cross-bearers extending from side sill to side sill, posts carried by the side sill and cross-bearers, a gusset riveted to the posts and extending down alongside of one of the cross-bearers, fastening devices extending through said gusset and cross-bearer below the floor of the car, a standard connected to the gusset, and means connected to the standard and car side for supporting a seat portion and back portion of the car-seat; substantially as described.

5. In a railway-car, the combination with a cross-bearer and upstanding posts, a gusset connected to one of the upstanding posts and an adjacent cross-bearer, a standard comprising a plurality of parts 10 and 11 provided with parallel flanges, means for securing one edge of the gusset between said flanges, and connections between said standard and the car side; substantially as described.

6. In a railway-car, the combination with cross-bearers and vertical posts, gussets secured to the sides of the car and extending below the floor of the car, connecting devices extending through said gussets and adjacent cross-bearers below the floor of the car, a standard secured to one edge of one of the gussets and having upwardly-converging flanges, oppositely-disposed seat-cushion supports connected to said standard; connections between the converging flanges of the standard and the side of the car, and connections between the seat-cushion supports and the side of the car; substantially as described.

In testimony whereof I hereunto affix my signature, in the presence of two witnesses, this 21st day of July, 1905.

ALLEN E. OSTANDER.
